TUBE MILL

Allan E. Alger, Lorain, Ohio, assignor to National
Tube Company, a corporation of New Jersey

Application October 14, 1935, Serial No. 44,949

1 Claim. (Cl. 80—13)

This invention relates to tube mills and particularly to those utilizing diagonal rolling rolls, one of the objects being to produce properly gaged tubes by means of such mills. Other objects may be inferred.

A specific example of the present invention is illustrated by the accompanying drawings, in which:

Figures 1 and 2 show a mill embodying the principles of the present invention and respectively show the two operating stages, described hereinafter, involved by its use, and

Figure 3 is a detailed sectional view of the latch and carriage construction.

The mill illustrated by the above drawings includes a set of diagonal rolling rolls 1, a carriage 2 arranged to reciprocate in line with the working pass of the rolls 1, a mandrel bar 3 rotatively mounted by the carriage 2 so as to project toward this working pass, a mandrel 4 mounted by the forward end of the bar 3 and a latch 5 for releasably preventing the carriage 2 from moving backwardly from a position where it holds the mandrel 4 in spaced relationship respecting the working surfaces of the rolls 1.

The above mill is intended to rotary-roll tube blanks to gage, and this gage is determined by the spacing of the mandrel 4 respecting the working surfaces of the rolls 1. To produce a properly gaged product this spacing must be measurable so that its proper maintenance is possible.

Continuing, the mill being described further includes an abutment 6 that is carried by the carriage 2 whereby it is arranged to move with the same, a lever 7 that is pivoted adjacent the reciprocative path of the carriage 2 so that one of its ends can be swung backwardly into contact with the abutment 6, a means 8 for urging this lever 7 to swing forwardly and away from the abutment 6, remotely indicating means 9 for measuring the extent the lever 7 swings and remotely operable means 10 for swinging the lever 7 backwardly into contact with the abutment 6.

More specifically, the lever 7 may be connected with a gear segment 7^a that meshes with a pinion 7^b, the means 8 may consist of a weight, the remotely indicating means 9 may consist of an indicating device provided with a suitably calibrated dial and connected to any conventional type of operating mechanism 9^a through a suitable cable 9^b, the transmitter 9^a being driven by the pinion 7^b, and the remotely operable means 10 may consist of a lever that is arranged to pull a rope 10^a that is bent around a series of sheaves 10^b so as to connect with the weight 8,

this rope passing over a quadrant 7^c that moves with the gear segment 7^a connected with the lever 7.

In operation, the mill operator moves the carriage 2 forwardly until the mandrel 4 contacts the working surfaces of the rolls 1. He then throws the lever 10 so as to pull on the rope 10^a and throw the lever 7 against the force of the weight 8 until this lever is swung backwardly into contact with the abutment 6, whereupon he notes the reading provided by the dial associated with the Selsyn receiver. Next he moves the carriage 2 backwardly until stopped by the latch 5 and again throws the lever 10 so as to again obtain a reading on the dial associated with the Selsyn receiver 9.

After the operator has done these things he can easily determine the distance it was necessary to move the carriage 2 from the position where the mandrel 4 contacted the working surfaces of the rolls 1 to one where the carriage was stopped by the latch 5. This is effected by a comparison of the two readings he obtained. Since the position where the carriage 2 is stopped by the latch 5 determines the working position of the mandrel 4, and since he knows the distance he had to move the carriage 2 to reach this position from one where the carriage was positioned to hold the mandrel 4 in contact with the working surfaces of the rolls 1, the operator consequently knows the distance this mandrel is spaced from these working rolls and is thus able to make whatever adjustments of the rolls or carriage are necessary as may be required to maintain the relation at a predetermined setting which will produce tubes of the required wall thickness having a minimum variation.

I claim:

In combination with a rotary rolling mill, of means for gauging the space between the mandrel and the working surfaces of the mill rolls to determine the necessary adjustment of the mandrel and mill rolls to produce a tube of the required wall thickness with a minimum variation, comprising an abutment carried by and movable with the mill mandrel-bar carriage, a lever pivoted adjacent the reciprocative path of said carriage, means adapted to move said lever into contact with said abutment and means operable by the movement of said lever for remotely indicating the relative forward and rearward movement of a mill mandrel-bar whereby a calculation of the difference in said readings will determine the adjustment necessary to obtain the proper spacing between the mill mandrel and mill rolls.

ALLAN E. ALGER.
